APPARATUS FOR CONDITIONING AIR

William R. Zuhlke, Yonkers, N. Y., assignor, by
mesne assignments, to American Radiator &
Standard Sanitary Corporation, New York,
N. Y., a corporation of Delaware

Application July 24, 1937, Serial No. 155,403

5 Claims. (Cl. 183—4)

My invention relates to air conditioning apparatus and more particularly to apparatus of this type which utilizes an absorbent material for removing moisture from air contacting therewith; the present application being a continuation in part of my copending application filed October 24, 1936, Serial No. 107,376, for Method and apparatus for conditioning air.

The general object of my invention is to provide an improved apparatus for conditioning air, and particularly air for ventilating rooms or spaces used for human occupancy.

My invention is characterized by, and comprises an improved apparatus for reducing the moisture content of, or dehumidifying air, and in some cases, its dehumidification is the only significant change in the condition of the air effected by the use of the invention. However, my method of dehumidification involves an initial heating and subsequent cooling of the air, and the air cooling operation may advantageously be carried out, in some cases, so as to make the delivery temperature of the conditioned air less than the initial temperature of the air conditioned.

In conditioning air in accordance with the present invention, I eliminate moisture from the air by bringing it into contact with some material, such as silicagel, calcium chloride or activated alumina, which in a dried, or activated, condition, is adapted to absorb a large amount of moisture from air brought into contact with the material, and which after having its moisture absorbing capacity reduced by the absorbed moisture which it holds, can have that capacity restored or increased, by a reactivation or regeneration treatment, which I effect by bringing into contact with the material, hot air admixed with products of combustion of fuel burned to heat the air. The words absorb and absorption, as used herein, are intended to generically include the action specifically designated by the words adsorb and adsorption.

Heretofore various proposals have been made for the use of absorbing material of the character above-mentioned, to dehumidify air and for the regeneration or reactivation of the material, from time to time, by bringing hot gases into contact with the material. My invention is characterized, however, by novelty in the means for, and method of carrying out and relating the dehumidification and regeneration steps or stages, by which the moisture absorbing material is alternately used as a dehumidifying agent and

is subjected to a regeneration or reactivation action.

My invention takes into account, and makes use of the fact that room atmosphere conditions suitable for the comfort and health of the room occupants may be maintained by the intermittent supply of an adequate amount of dehumidified air to the room, and that if the periods during which air is supplied are suitably long, and alternate with periods suitably short in which the supply of fresh air is interrupted, the general ventilation and conditioning effect will be practically equivalent to that obtainable by the continuous supply of substantially the same amount of fresh air to the room. While the precise duration of the successive dehumidifying and regenerating stages of the cyclic operation which are provided, may vary with conditions, I note by way of example, that a preferred form of apparatus for the practice of my invention, hereinafter described in detail, was designed, and is adapted, for successive operation cycles, each comprising a dehumidification stage or period of about 25 minutes, and a regeneration, or activation stage or period of about 12 minutes, and a purging stage or period of about 3 minutes.

In the preferred form of my invention I continuously move air, drawn directly from the atmosphere or other source of air to be conditioned, into contact with the moisture absorbing material by which the air is dehumidified. During the dehumidification stage or period of each cycle, the air after passing out of contact with the moisture absorbing material, is subjected to a cooling action to suitably lower the temperature of the air, which is raised, while in contact with said material, by the addition to the air of sensible heat corresponding in amount to the latent heat of evaporation of the moisture absorbed from the air by the material. During each regeneration, or reactivation, period or stage, the air is subjected to a heating action, suitably diminishing the relative humidity of the air, prior to the passage of the air into contact with the absorbing material then being regenerated or reactivated, and the air then passing out of the contact with the absorbing material, and carrying with it the moisture which it drives out of that material, is diverted from the air cooling means used in the dehumidification stage and from the room or rooms ventilated, and is ordinarily discharged to waste.

The capacity for the regeneration of the material in a fraction of the time in which the material is used in dehumidifying ventilation air, is

made practically possible in accordance with the present invention, by the use of simple and effective means for heating the regeneration air approximately to the maximum temperature to which the absorbing material can be safely and economically subjected, and by disposing the moisture absorbing material relative to the path of air flow, so as to insure a desirably extended and close contact of the air with said material.

For the practice of my invention, I have devised a novel air conditioning apparatus unit of such character that it may be located in the cellar or furnace room of an ordinary dwelling house of moderate size, and used to condition the air for ventilating some or all of the various rooms of the house. Said unit is adapted, however, for use, with no significant change except in its dimensions, to provide conditioned air in larger amounts, as required, for example, in the ventilation of office buildings, and of restaurants, theatres, and other large assembly rooms.

The improved unit in its preferred form is especially adapted for domestic use and without requiring skilled attendance, by the mechanically simple and reliable character of the provisions for carrying out, and for automatically repeating the dehumidification and regeneration actions at regular intervals.

The air cooling action to which the dehumidified air is subjected, may be effected by mechanical refrigeration means, by the use of cooling water drawn from city water supply mains or other available source of cooling water, and by other means, and the character of the cooling means desirably employed in different installations, will ordinarily depend on cost and convenience considerations which will vary in different installations. Wherever it is especially desirable, or the cost of the additional cooling required is not economically objectionable, the cooling action may be carried out so as to make the delivery temperature of the conditioned air appreciably lower than the temperature of air supplied for conditioning. For ordinary ventilation purposes, in localities and under conditions in which I anticipate that the greatest practical use of the invention will be made, practically effective and satisfactory air conditioned results are obtainable without any significant reduction in the temperature of the conditioned air below the prevailing atmospheric temperature, since, for example, air at a temperature as high as 85 or 90° F., in ordinary rooms, does not seriously inconvenience or give discomfort to the occupants of the room, provided the humidity of the air is suitably low.

For installations in which it is not convenient, or is too expensive, to cool the air by other means, I may cool the air by an evaporative action in a heat exchanger comprising passages for the air to be cooled which are in good heat transfer relation with passages through which I pass atmospheric air after spraying water into that air. With such evaporative cooling, it is practically possible to reduce the temperature of the conditioned air appreciably below the atmospheric dry bulb temperature.

In addition to the general features mentioned above, my improved apparatus in preferred forms, comprises various novel features of construction and arrangement. While the various features of novelty which characterize the invention are pointed out with particularity in the claims annexed to and forming a part of this specification, for a better understanding of the invention and its advantages, reference may be

had to the accompanying drawings and descriptive matter in which I have illustrated and described preferred embodiments of my invention.

Of the drawings:

5 Fig. 1 is a perspective view of a preferred form of an air conditioning unit constructed in accordance with the present invention;

10 Fig. 2 is a vertical section on the plane indicated by the line 2-2 in Fig. 1, and in Fig. 3;

Fig. 3 is a vertical section on the line 3-3 of Fig. 2;

Fig. 3A is a partial horizontal section on the line 3A-3A of Fig. 3;

15 Fig. 4 is a diagrammatic representation of control provisions included in the unit shown in Figs. 1, 2, and 3;

Fig. 5 is a vertical section on the line 5-5 of Fig. 6, of a unit of modified form; and

Fig. 6 is a vertical section on the line 6-6 of Fig. 5.

The air conditioning unit shown in Figs. 1, 2, and 3, comprises a casing or housing 1, rectangular in its horizontal and vertical cross sections, and of any suitable construction. As shown, its walls are formed of sheet metal, and its vertical walls include panels 2, removable to permit access to the interior of the casing. Ordinarily, the casing walls will include or be covered by heat insulating material, not illustrated. An air inlet conduit 3, a waste heat air outlet conduit 4 and a conditioned air outlet conduit 5, respectively communicate with different portions of the space within the casing 1, through ports 3A, 4A and 5A, respectively in the casing top wall.

The conduit 3 which ordinarily has its inlet end exterior to the building in which the unit is located, supplies to the plenum space 1A within the unit casing 1, the air which is to be conditioned, and the air which is used in the reactivation of the dehumidifying material. From the plenum space 1A, the air passes in to one end of a horizontal conduit 6 adjacent the top of the unit. The air entering the conduit 6 is heated during activation periods by the hereinafter described gas burner 7, the latter being inoperative during periods in which the unit is used in dehumidifying air. At its end remote from the burner 7, the conduit 6 delivers air to the upper end of a subjacent vertically disposed conduit 8. The latter delivers air through vertically distributed, horizontally elongated ports 9 in a vertical wall which forms a common side wall for the conduit 8 and for the housing enclosing a dehumidifying space or chamber 10. As shown, the channel 8 diminishes in cross section from its upper to its lower end, so as to maintain an approximately uniform vertical air velocity in the conduit, to facilitate the proper distribution of flow through the ports 9.

Within the space 10, which, as shown, is rectangular in its horizontal and vertical cross sections, are located a plurality of superposed dehumidifying bodies or layers 11, vertically spaced apart, of moisture absorbing material. The layers 11 are preferably, of approximately uniform thickness and each extends horizontally across the space 10, and is supported by a perforated screen or tray 12. The material in the layers 11 may be any one of various known available materials adapted to absorb water and to be reactivated as described herein, but for practical commercial reasons, I now consider it ordinarily preferable to employ the comminuted material known as activated alumina. The previous trays or

screens 12 may take various forms. At the present time, I preferably form them of black iron sheets of about 24 gauge, with about 200 perforation per square inch, and with each perforation about $\frac{1}{64}$ " in diameter. In the type and form of apparatus shown, the thickness of each layer 11 and of the free air space between the top of each layer and the supporting tray 12 for a layer above it, may well be 4 or 5 inches. The dimensions just stated are not critical, and are given by way of illustration, and not by way of limitation.

The air entering the space 10 through ports 9 at one side of said space, leaves the space through vertically distributed, horizontally elongated ports 13 in the vertical wall at the opposite side of said space. As is clearly shown in Fig. 2, the ports 9 are vertically spaced twice as far apart as are the dehumidifying tray 12 and layers of material, 11. The vertical spacing of the ports 13 is the same as that of the ports 9, but the levels of the ports 13 are staggered with respect to the levels of the ports 9. As shown, each port 13 opens directly to, and forms the only air outlet from the space between the two layers of material 11 of a corresponding pair of said layers. There is a port 9 opening into the space above the uppermost layer 11, and another port 9 opening into the space below the lowermost layer 11, and the intermediate ports 9 open in the spaces between layers 11 which alternate with the spaces to which the ports 13 open.

In consequence, air entering the chamber 10 through any port 9 cannot pass out of the chamber except after passing through a layer 11 interposed between the port and a port 13. There are thus normally similar paths of flow through the space 10 between each intermediate port 9 and the two ports 13 one at a level immediately above, and the other at a level immediately below the level of the port 9. The described arrangement of the ports 9 and 13 thus contributes to a flow distribution through the space 10, making effective use of all portions of all of the bodies or layers 11, and minimizing the objectionable effects of nonuniformity in thickness, perviousness, or water absorbing capacity of different portions of the different bodies 11.

The ports 13 open into a vertically disposed outlet passage 14 which increases in horizontal cross section from its top to its bottom, to facilitate the distribution of flow through the chamber or space 10. Adjacent its lower end, the conduit 14 communicates with the adjacent end of a horizontal conduit or passage 15 underlying the chamber 10 and traversed by the tubes of a tubular air cooler 16. At its opposite end, the passage 15 opens into a chamber or conduit 17, elongated in a direction transverse to that of the conduit 15. The chamber or passage 17 communicates at one end with the inlet eye 18 of the casing of a fan 19 which draws air through the dehumidifying chamber 10 and air cooler 15, and delivers air through the fan delivery conduit 20 to the housing outlet 5A and conduit 5 in the dehumidifying stages of operation of the apparatus. During reactivation periods, alternating with the dehumidification periods, the air entering through the conduit 14 through the ports 13, is withdrawn from the conduit 14 by a fan 22 having its casing inlet eye 21 opening to the lower portion of the conduit 14 through a side wall of the latter. The outlet from the casing of the fan 22 is connected by a conduit 23 to the waste air outlet 4A and discharge conduit 4.

The fan 22 is shown as driven by a directly connected driving motor 24, and the fan 19 is similarly driven by a motor 25 shown in Fig. 4. As collectively appears by Figs. 2 and 3, space for the two fans, their delivery conduits, and driving motors is provided at one side of the chamber 10 and between the latter and adjacent the vertical side wall of the housing 1. The described arrangement is practically desirable and important in some cases, because it contributes to compactness, permitting of the convenient arrangement of the unit in a cellar or furnace room of restricted dimensions.

The described arrangement permits the rectangular horizontal cross section of the dehumidifying chamber 10 to be square or approximately square. Similarly, the horizontal cross section of the housing 1 may approximate a square, with the dehumidifying chamber nearer to one, than to the other, of two opposing side walls of the housing, to provide space at one side of the chamber for the fans and their delivery conduits, and with the other two housing walls spaced from the adjacent walls of the chamber 10, to provide space for the conduits 8, 14, and 11. The described shape of the apparatus permits of practically maximum compactness to the chamber 10 and housing 1, but except as compactness facilitates the use of the apparatus in restricted spaces and as it may contribute to some economy in housing construction, the features of form and shape just referred to, are unimportant.

The air heater 7, which may take various forms, is shown as comprising two similar hollow castings arranged one above the other. Each casting comprises a central portion 30 and four arms 31, there being an upper and a lower arm extending horizontally away from the central portion 30, at each side of the latter. The eight arms 31 are thus arranged like the bars of a gridiron, and collectively extend across the inlet end of the passage 6. The central portion 30 of each burner casting receives gas and primary combustion air through a corresponding horizontal mixing tube 32. Each mixing tube receives a stream or jet of gas from a vertical supply pipe section 33 at one side of the passage 6, and said stream or jet aspirates primary air into the mixing tube through an air inlet (not shown), as is customary in the operation of Bunsen type gas burners. The pipe section 33 is connected by a horizontal pipe section 34 to the outlet of a main control valve 35, which has its inlet connected to the gas supply pipe 36. Each of the superposed arms 26 of each casting are connected at their outer ends.

The burner arms 31 are formed with burner orifices or outlets at their sides adjacent the passage 6 for the discharge into the latter of streams or jets of gas mixed with primary air for combustion, the secondary air for combustion being furnished by the air stream then being drawn into the passage 6 from the plenum chamber 1A, through the rectangular air ports above, and below each arm 31. As shown, each arm 31 constitutes a burner element of the so-called ribbon type, being formed with an outlet slot extending for substantially the full length of the arm, in which is packed strip metal 37, bent to form a multiplicity of fine burner orifices. The elongated air ports above and below each arm 31 insure a flow into the passage 6, distributed uniformly across the passage 6, which is desirable because it contributes to efficient combustion, and to a substantial uniformity in

mixture and temperature of the air and the products of combustion flowing from the passage 6 through the conduit 8 into the chamber 10, to activate or regenerate the material in the layers or bodies. One of the burner castings is formed with outlet 38 for discharging a jet of the gas and primary air mixture adapted to be ignited by the flame from a pilot burner 39, the purpose of operation of which is hereinafter described.

The walls enclosing the dehumidifying space 10 and the passages or conduits 6, 8, 14, 15, and 17, may well be formed of sheet metal parts connected in any usual or suitable manner, except that provisions ordinarily should be made for placing the moisture absorbing material layers in place in the apparatus, after the operation of assembling the apparatus in its place of use has progressed so far that its completion will not disturb the distribution of the granular moisture absorbing material 11 supported by the trays 12. To this end, in the form of construction shown, the vertical wall of the chamber 10 at the side of the latter remote from the fans 19 and 22 is advantageously formed of separable superposed horizontally extending sections, comprising a bottom section 40 intermediate sections 41, and a top section 42, which can be put in place after the trays 12, are anchored in place, and have had distributed over them the material constituting the layers 11.

As shown, tray supporting angle bars 43 are spot-welded or otherwise secured to the wall of the chamber 10, adjacent the fans, and to the walls in which the ports 9 and 13 are formed, to provide supports for three side edges of each tray 12. At its fourth side edge, each tray 12 is provided with a supporting part 44. The latter as shown, is in the form of a strip of sheet metal having a vertically disposed body portion with a transversely bent lower edge portion 45. The latter extends beneath, and is connected, as by spot-welding to the tray 12. Each member 44 has transversely bent outwardly extending end portions 46 secured as by means of bolts 47 to the corresponding edge portions 47 of the opposed walls of the chamber 10 in which the ports 9 and 13 are respectively formed.

In assembling the trays 12 and absorbing layers 11, the lowermost tray 12 is first put in place. The proper weight of layer forming material is then deposited and distributed over the tray. Ordinarily, the distribution is effected by the hand of the operator. The next highest tray 12 is then secured in place, and given its layer 11 in the manner described, and the operations are repeated, tray by tray until the uppermost tray and layer are in place. As will be apparent, the operation of distributing the layer material over the trays will not be impeded by space restrictions, except as it may be to a certain extent in the case of the uppermost tray and layer.

The bottom wall section part 40 is formed at its lower edge with an outturned flange portion abutting against the metal plate constituting the bottom wall of the chamber 10 and the top wall of the passage 15. The sheet metal from which the section 40 is formed is bent or folded to provide a vertical groove 48 at the top of the section, the groove being open at its upper side, and to provide an inner depending skirt portion 49. In the assembled apparatus, the skirt portion 49 of the section 40 is in overlapping relation with, and at the innerside of the body portion of the supporting part 44 secured to the

lowermost tray 12. Each intermediate section 41 differs from the bottom section 40 only in that its lower portion is not flanged, but constitutes a flat tongue entering and snugly received in the groove 48 of the immediately subjacent section. The top wall section 42 is of L shape in cross section, comprising main vertical portion which has its lower edge received in the groove 48 of the subjacent section 41, and an outturned upper horizontal portion which abuts against the metal plate forming the top wall of the chamber 10 and the bottom wall of the passage 6.

The air cooler 16 in the passage 15, may take any usual or suitable form. As shown, it comprises a plurality of horizontal tubes 50 extending across the passage 15 at each of a plurality of different levels. The tubes 50 at each level, are connected by return bends 51 to provide a continuous serpentine flow path for water from an inlet header 52 at the end of the cooler adjacent the chamber 17 and an outlet header 53 at the end of the cooler adjacent the conduit 14. Water is supplied to the inlet header 52 by a supply pipe 54 (see Fig. 4), the flow through which is controlled by a valve 55 automatically opened and closed as hereinafter described.

The tubes 50 extend through vertical metal plates 56 and 57 extending longitudinally of the passage 15. The vertical plates 56 constitute the side walls of the passage 15 and form the main supports for the tubes 50. The plates 57 are spaced to divide the passage 15 into a multiplicity of narrow, vertically elongated channels, and have driving fits with the tubes 50, or are otherwise associated therewith to be in good heat conductivity relation with the tubes, so as to increase the rate of heat transfer from the hot air moving through the passage 15, to the cooling water moving through the tubes 50.

In the intended operation of the apparatus shown in Figs. 1 to 4, the fan 19 operates and the fan 22 does not operate during the dehumidification stage, and it is then desirable that all of the air moved by the fan 19 should be drawn through the dehumidifying chamber 10, and that there should be no backflow through the conduits 4 and 23 and the casing of the fan 22. Such backflow is prevented in the apparatus shown by a check valve 60, and a similar check valve 60A is provided to prevent backflow from the room or rooms supplied with conditioned air, through the conduits 5 and 20 and the casing of the fan 19, when the latter is out of operation and the fan 22 is in operation during the activation and purging periods.

As collectively shown in Figs. 2 and 3, the waste air outlet element 4A is larger in horizontal cross section than the upper portion of the conduit 23 and projects laterally outward from the upper end of the conduit 23 at all sides of the latter, and thereby provides a seat for the check valve 60. The latter is advantageously of such light weight that it will be lifted from its seat into, and held in its wide open position by the air flowing upward through the conduit 23, when the fan 22 is in operation, without creating any significant back pressure or resistance to the flow of air from the conduit 23 into the outlet 4A. When the normal operation of the fan 22 is interrupted, terminating the upflow through conduit 23, the valve 60 will drop into engagement with its seat under the action of gravity and the suction of the fan 19. The valve member 60 may be formed of suitable sheet metal, such

as stainless steel, but in the form shown, comprises a sheet of asbestos reinforced by a pair of parallel light weight metal bars or strips 61 secured to the asbestos and a pair of similar bars or strips extending transversely of and secured to the bars 61. Barlike parts 63, secured in the outlet 4A at a suitable level above its lower end, form stops which arrest the up-movement of the valve member 60, and against which the latter is held by the air stream when the fan 22 is in operation.

The check valve 60A may be exactly like the valve 60, and the outlet 5A is shaped to provide a seat for the valve 60A, similar to the seat for the valve 60 formed by the outlet 4A.

In the intended normal operation of the apparatus shown in Figs. 1, 2, and 3, during each dehumidification period of about 25 minutes, the motor 25 driving the fan 19 is in operation, the valve 55 in the water supply pipe leading to the air cooler 16 is open, the fan motor 24 is out of operation, and the main gas supply valve 35 is closed.

The extent to which the air drawn into the apparatus through the fresh air supply conduit 3, is dehumidified in the dehumidification stage of operation, depends upon such design factors as the area and thickness of the moisture absorption layers 11, the moisture absorbing capacity of the material in those layers, and the weight rate of air movement through the layers. I now consider it good practice to design a unit of the character shown in Figs. 1, 2, and 3, so that in normal operation about 70% of the moisture content of the fresh air will be removed from the air as it passes through the dehumidification chamber 10.

As is well known, the moisture absorbing action of the material in the layers 11 is adiabatic and the passage of the air being dehumidified through the layers 11, increases the temperature of the air in correspondence with the latent heat of evaporation of the moisture absorbed, substantially all of such latent heat being transferred to the air. The extent to which the air is cooled in its passage through the air cooler 16 depends upon the cooling capacity of the cooler. In general, that capacity, at least, should be sufficient to eliminate the increase in dehumidified air temperature occurring in the passage of the air through the dehumidifying chamber 10. The cooler 16 can be designed and operated to cool air to a temperature below the atmospheric air temperature, when the conditions make it worthwhile to provide the additional cooling effect required.

During each activation or regeneration period of about 12 minutes which immediately follows each dehumidifying period, the fan motor 24 is in operation, the main gas valve pipe 35 is open, the fan motor 25 is out of operation, and the cooler water supply valve 55 is closed. At the end of each activation period, the only change in the operative condition of the apparatus made to initiate the purging period of about 3 minutes which follows the activation period, and precedes the subsequent absorption period, consists in the closure of the main gas supply valve 35. During the purging period, the hot activating mixture of air and products of combustion produced by the burner, are fully expelled from the apparatus and the latter is cooled by the flow of air then unheated which is moved through the apparatus by the fan 22.

It is necessary, of course, that the amounts of

moisture driven out of the absorbing material in the layers 11 during the activation periods, must equal the amounts of moisture absorbed by the material during the dehumidification stage. The capacity of the apparatus to eliminate moisture from the absorbing material in the layers 11 during each activation period, depends upon the weight rate of air flow through the chamber 10, and the relative humidity of the air, and the temperature to which the air is heated by the heater 7. While in designing the apparatus considerable latitude is permissible in respect to the activation air velocity and temperature, in general, the air velocity must not be high enough to involve risk of displacement of the material in the beds 11, or high enough to result in an undesirably large differential between the pressures in the conduits 8 and 14. It is desirable also that the temperature to which the air is heated by the burner 7 should not be high enough to involve an objectionably large amount of heat radiation to the atmosphere in the room in which the unit is located, or to create a fire hazard, or to so attenuate the air heated as to objectionably increase the air pump capacity required.

A control system or arrangement for automatically starting and stopping the motors 24 and 25, and for controlling the gas and water valves 35 and 55, respectively, and for serving certain hereinafter mentioned safety purposes, is illustrated in Fig. 4. In the arrangement shown in Fig. 4, the timing of the dehumidifying, activating and purging stages of each of the recurrent operating cycles of the apparatus, is automatically effected by a time clock controller 73 including an electric driving and timing motor 72, energized from electric supply conductors 70 and 71. The time clock 73 may be and as shown is, of a commercial type, and comprises switch members 74 and 75 given clockwise opening and counterclockwise closing adjustments at regularly recurring time intervals while the motor 72 is in operation, through cams actuated by said motor.

The control system and the conditioning apparatus which it controls, are put into and out of operation by the closure and opening of a so-called owner's switch 76. The closure of that switch energizes the time clock motor 72 through a circuit comprising the supply conductor 70, conductor 71, switch 76, conductor 78 running to one terminal of the motor 72, and conductors 79 and 80 connecting the other terminal of the motor 72 to the supply conductor 71. If the activation or purging stage of the operation cycle is being carried out when the owner switch 76 is opened, the apparatus will continue in operation until the time clock is in condition to initiate the subsequent dehumidification stage. This result is secured by means of an auxiliary energizing circuit for the motor 72, which is closed whenever the activation motor 24 is in operation. The auxiliary clock energizing circuit comprises a supply conductor 71, conductors 80 and 79, the terminals of the motor 72, a portion of conductors 78, a conductor 81, the switch blade 82 of an electro-magnetic switch 83 and a conductor 84 which connects the blade 82 to the supply conductor 70, when the electro-magnetic switch is energized, as it is when the motor 24 is in operation.

Under normal conditions, the closure of the owner's switch establishes an energizing circuit for the driving motor 25 for the dehumidifica-

tion fan 19 and a circuit for opening the valve 55 controlling flow through the water supply pipe 54 for the cooler 16. The energizing circuit for the motor 25 then closed, includes supply conductor 70, conductor 71, switch 76, conductor 78, conductor 81, switch blade 82, conductor 85 leading from one contact of the switch 83 to one terminal of the motor 25, and a conductor 86 through which the second terminal of the motor is connected to the supply conductor 71. The circuit closed to open the valve 55, which is an electro-magnetic valve biased to closed, includes a conductor 87, connecting one terminal of the valve 55 to the conductor 85 and thereby to the supply conductor 70, and a conductor 88 connecting the second terminal of the valve to the supply conductor 71.

The dehumidification period or stage is terminated at the proper time by the time clock 73 which then closes the switch 75, and then, 20 seconds or so later, closes the switch 74. The closure of the switch 75 energizes the winding of the electro-magnetic switch 83 by closing a circuit including supply conductor 70, conductor 77, switch 76, conductor 78, switch 75, conductors 89 and 90, winding of switch 83, conductor 80 and supply conductor 71. When the winding of switch 83 is energized, the switch blade 82 is turned downward against the action of its bias spring, to break engagement with the conductor 85 and thereby open the energizing circuit for the motor 25 and the energizing circuit for the valve 55. This interrupts the operation of the fan 19 and interrupts the supply of cooling water to the cooler 16. When the switch blade 75 connects the conductors 89 to the supply conductor 70, it also completes an energizing circuit for the activation fan motor 24, to one terminal of which the conductor 89 is connected, is connected by a conductor 88. The second terminal of the motor 24 is connected to the supply conductor 71 through the conductor 86.

When the time clock gives a closing adjustment to the switch 74, it closes the primary circuit of a transformer 91, the secondary of which supplies current for energizing the motor mechanism of the main gas valve 35 to open the latter. The primary circuit of the transformer 91, comprises supply conductor 70, conductor 71, switch 76, conductor 78, switch 74, conductor 92, thermostatically controlled switch 93, primary winding of transformer 91, conductor 94, and supply conductor 71. The terminals of the transformer secondary are connected to the terminals of the motor valve mechanism by conductors 95 and 96, respectively.

The operating mechanisms of the valves 35 and 55 need not be illustrated and described in detail herein, since each of those valves may be of a known commercial type. The valve 35 is biased to its closed position, and is opened by the operation of a low voltage motor. The closure of the switch 74 and opening of the gas valve 35 is delayed for 20 seconds or so, following the closure of the switch 75, to permit the speed of the activation fan 22 to build up, and start an air movement through the activation path of flow, before the burner 7 is started into operation by the opening of the gas valve 35. As soon as the valve 35 is opened and gas begins to pass out of the burner through the outlet 37, the burner is ignited by the flame from the pilot burner 38.

The switch 93 in the primary transformer cir-

cuit, is normally closed, but is adapted to open automatically, to de-energize and close the main gas valve 35, if and when the temperature of the air and gas activation mixture in the conduit 8 attains a safe maximum temperature of 600-630° F., which should not be exceeded. On the attainment of that temperature in the conduit 8, a thermally responsive device 97, extending into the conduit 8 opens the switch 93. The device 97 may be a bimetallic thermostatic switch or a fluid pressure thermometer bulb, and the operating connection between it and the switch 93, may be an electrical conduit or a pressure transmitting connection 98.

The gas supply line includes an automatic gas valve 99, of known commercial type. The valve 99 is adapted to close when the pressure transmitted to it by a thermometer bulb 100 is reduced on the extinction of the pilot light, or when the pressure transmitted to it from a thermometer bulb 102 is increased from that corresponding to normal atmospheric temperature to that corresponding to a temperature of 220° or so. The bulb 100, as shown, is coiled about the pilot burner 38 so that the bulb pressure may be quickly responsive to the operation or non-operation of the pilot light. The thermometer bulb 102 is located in the fresh air inlet 3A, but is not intended to respond operatively to variations in atmospheric temperature. It serves a safety device purpose, in that it is adapted to cut off the supply of gas to the burner 7 and also to the pilot burner 38, when, as a result of fan failure or some analogous operating defect, the normal movement of the air through the apparatus is interrupted, and as a result of burner operation, the temperature in the apparatus builds up to the point at which the back flow through the conduit 3 heats the bulb 102 to its operating temperature of 220° F., or so.

As shown in Fig. 4, the pilot burner 38 normally receives gas through a branch supply pipe 103 connected to the main gas supply pipe 36 between the outlet of the cutoff valve 99 and the inlet of the main control valve 35. The closure of the latter valve does not interrupt the operation of the pilot valve, but the closure of the valve 99 does extinguish the pilot burner flame. In restarting the apparatus into operation, following a period in which the pilot valve has been out of operation, gas may be supplied to the pilot burner for operation of the latter long enough to heat up the thermometer bulb 100, and thereby open the valve 99, by opening a normally closed push-button valve 104 in a by-pass 105 between the portion of the main supply pipe 36 at the inlet side of the valve 99 and the pipe 103.

If the temperature in the conduit 14 attains an unduly high value of 350 or 360° F. or so, at any time, it is an indication that the apparatus is operating unsatisfactorily, and should be shut down for inspection and adjustment or repairs. With the arrangement shown in Fig. 4, such an interruption in the operation of the apparatus is effected automatically by means of a thermometer bulb or other temperature responsive device 106, extending into the conduit 14, and a pressure transmitting or other actuating connection 107 between the temperature responsive device 106 and a normally open valve 108 in the gas supply line at a point in the gas supply piping for the pilot burner at the outlet sides of the valves 99 and 104. The valve 108 is biased for adjustment into its open position,

but is adapted to be closed when the thermally responsive device 106 attains the temperature which should not be exceeded. The closure of the valve 108 results in the extinction of the pilot flame, and the closure of the valve 99, and thereby interrupts the operation of the burner 7.

In Figs. 5 and 6, I have illustrated a dehumidifying unit differing in some respects from that shown in Figs. 1 and 2, and 3. The unit of Figs. 5 and 6 comprises a housing 1A generally like the housing 1, and is provided with a fresh air inlet 3B, a conditioned air outlet 5B, and a waste activation air outlet 4B, corresponding to the inlet 3A and outlets 5A and 4A, respectively of the construction first described. The apparatus of Figs. 5 and 6 includes a burner 1A, a dehumidifying chamber 10A and a cooler 16A which may be identical with the element 7, 10, and 16 of the construction first described. The apparatus of Figs. 5 and 6 also includes passages 6A, 8A, 14A, 15A, and 17A, corresponding generally to, though differing somewhat in form from the passages 6, 8, 14, 15 and 17 of the construction first described.

The principal operative differences between the two units, is that in the unit of Figs. 5 and 6, the conditioned air fan 19A and the activation fan 22A, are directly connected to the shaft of the same common driving motor 110 which is a reversible motor and operatively actuates the fan 19A only when operating in one direction, and operatively actuates the fan 22A only when operating in the opposite direction. To permit of the side by side coaxial relation of the two fans, the inlet eye of the fan 22A is connected to the passage 14A by a conduit 111, located at one side of the dehumidifying chamber 10A and communicating with the passage 14A through a port 112. A check valve 60B, shown as a pivoted or flap valve, is provided to prevent backflow from the outlet 5B to the casing of the fan 19A through its delivery conduit 20A. A similar check valve 60C is employed to prevent backflow from the outlet 4B to the fan 22A through its delivery conduit 23A. The operating cycle of the unit shown in Figs. 4 and 5, may be exactly the same as that of the unit first described, and the unit of Figs. 5 and 6 may be provided with automatic control and safety provisions like or analogous to those shown in Fig. 4. The unit of Figs. 5 and 6, has the advantage of making use of but a single fan driving motor, but the use of a separate driving motor for each fan in the unit first described, has a compensating advantage in that it permits each fan and its driving motor to have the design and the proportions most suitable for its conditions of operation. With each of the two units already described, I consider it ordinarily desirable to move air to be dehumidified, and air and products of combustion for activation through the chamber 10 or 10A at about the same weight rate. This means that the capacity of the activation fan, 22 or 22A, must be appreciably greater than that of the absorption fan 19 or 19A, because of the higher temperature and greater volume moved by the activation fan 22 or 22A.

The unit shown in Figs. 1, 2, and 3 has a definite advantage from the standpoint of compactness over the unit of Figs. 5 and 6, where conditions make an approximation to a square horizontal cross section of the unit housing desirable. As will be apparent, the horizontal extent of the unit of Figs. 5 and 6 in the direction

5 of the plane of Fig. 6 is necessarily greater than is required for the transverse horizontal dimension of the unit, since as seen in Fig. 6, the passage 14A, chamber 10A, passage 8A, and fan delivery conduits are arranged alongside of one another, whereas in the transverse direction, the housing really needs to be only wide enough to accommodate the side by side outlets conduits 4B and 5B.

In both forms of the invention illustrated, the air flow through the unit, in each stage of operation is along a flow path including an initial down component followed by an up component. This contributes to unit compactness, which is of especially importance in adapting the invention for ready use under such spatial restrictions as prevail when the unit is located in the cellar or basement of a moderate size dwelling house.

20 As already indicated, the various control valves shown in Fig. 4 may be of commercial types. For example, the main gas valve 35 may be a valve known as the Minneapolis-Honeywell V-15-5 No. 566 V-15-5, and the valves 55, 99 and 108 may be Detroit Lubricator Company valves, known as type S solenoid valves, gas valve No. 586 VF, and stack limit control valve No. 273, respectively. Also, the limit switch 93 of Fig. 4, may well be a device manufactured by the Detroit Lubricator Company and known as its furnace control No. 286.

25 While in accordance with the provisions of the statutes, I have illustrated and described the best forms of embodiment of my invention now known to me, it will be apparent to those skilled in the art that changes may be made in the form of the apparatus disclosed without departing from the spirit of my invention as set forth in the appended claims and that in some cases 30 certain features of my invention may be used to advantage without a corresponding use of other features.

35 Having now described my invention, what I claim as new and desire to secure by Letters Patent, is:

40 1. Apparatus for dehumidifying air, comprising an enclosed chamber with the wall at one side of said chamber formed of separable superposed sections, superposed previous beds within and extending across said chamber and each comprising a tray supporting a layer of granular material which is adapted to absorb moisture from relatively cool humid air and to give up moisture to relatively hot dry air, supporting means within said chamber for supporting the different trays, each tray being movable into place in said chamber and into engagement with the said supporting means therefor through the said side of said chamber when said sections are not in place, whereby each tray may be put in place in said chamber and the material forming the said layer supported by the tray may be spread out over the tray prior to the putting in place of any tray at a higher level, means for securing said superposed sections in place, said trays and sections having vertically disposed portions adapted to overlap and interlock adjacent sections with one another and to interlock each tray with an adjacent section.

45 2. An air conditioning unit comprising a base supporting member; an enclosing jacket having an air inlet, a conditioned-air outlet, and a waste-air outlet all located in the upper part thereof; a dehumidifier casing arranged within said jacket and supported by and above said

member and containing moisture-absorbing material; a cooling conduit including air cooling means supported by said member and arranged between the latter and said casing; a conditioned-air fan and a waste-air fan in the lower portion of said jacket and supported by said member; conduit means providing for the movement of air over a permanent flow path including the jacket inlet, across the top and down along one side of said casing, through the latter and over the material therein and out through the side opposite its entrance, and then for the movement of such air over two alternative flow paths, one alternative path including said cooling conduit, said conditioned-air fan and said conditioned-air outlet and the other alternative path including said waste-air fan and said waste-air outlet; control means providing for the movement of air along said permanent flow path and said one alternative flow path for dehumidification periods, and along said permanent flow path and said other alternative flow path for reactivation periods; heating means in said conduit means ahead of said casing; and means for operating said heating means during reactivation periods only.

3. An air conditioning unit comprising an enclosing jacket having an air inlet, a conditioned-air outlet, and a waste-air outlet; a body of moisture-absorbing material in said jacket; air heating means in said jacket; a conditioned-air fan; a waste-air fan; conduit means providing a first flow path for air including said inlet, said body of moisture-absorbing material and said conditioned-air fan and outlet and providing a second flow path including said inlet, said heating means, said body of material and said waste-air fan and outlet; control means providing for the operation of said conditioned-air fan and for the non-operation of said waste-air fan and heating means during dehumidification periods, and for the operation of said waste-air fan and heating means and non-operation of said conditioned-air fan during periods of activation of said material; non-return valve means in said conduit means between the conditioned-air fan and outlet and preventing reverse flow of air therethrough during activation periods; and a second non-return valve means between the waste-air fan and outlet and preventing reverse flow of air therethrough during dehumidification periods.

4. An air conditioning unit comprising a base supporting member; an enclosing jacket having an air inlet, a conditioned-air outlet, and a waste-air outlet all located in the upper part thereof; a dehumidifier casing arranged within said jacket and supported by and above said member and including a pair of opposed upright side wall parts having air inlet and outlet openings, respectively, formed therein; said casing containing a moisture-absorbing material adapted to be contacted by air flowing therethrough; a cooling conduit including air cooling means

and extending between the bottom of said casing and said member and from a point beneath the air outlet side of said casing toward a point beneath the inlet side thereof; a waste-air fan in the lower part of said jacket and adjacent the outlet side of said casing and supported by said member; a conditioned-air fan in the lower part of said jacket and adjacent the inlet side of said casing and supported by said member; heating means in the upper part of said jacket; and means providing for the flow of air through said jacket inlet, over said heating means, over the moisture-absorbing material, and through the cooling conduit and conditioned-air fan and upward to the conditioned-air outlet during dehumidification periods, and providing for the flow of air from said jacket inlet over said heating means, over the moisture-absorbing material and through the waste-air fan and upward to the waste-air outlet during reactivation periods, and including means for operating said heating means only during reactivation periods.

5. An air conditioning unit comprising a base supporting member; a cooling conduit extending along said member and having an inlet at one end and an outlet at the opposite end; air cooling means in said conduit; a conditioned-air fan supported by said member and having an inlet connected to the cooling conduit outlet; a casing structure supported by said member and above said cooling conduit and having one upright end wall adjacent the inlet and another upright end wall adjacent the outlet of said cooling conduit, and said end walls having air openings therein; an upright manifold connecting the air openings of said one end wall with the cooling conduit inlet; a waste-air exhaust fan supported by said member and having an inlet connected to said manifold means; a heating conduit extending along the top of said casing and having an inlet adjacent said one end wall and an outlet adjacent said other end wall; heating means in said heating conduit; a second upright manifold connecting the heating conduit outlet with the openings in said other end wall; a jacket structure enclosing the above-mentioned elements and having an inlet connected to the heating conduit inlet, an outlet connected to the discharge of said conditioned-air fan, and an outlet connected to the discharge of said waste-air fan; moisture-absorbing material positioned in said casing to be contacted by air flowing therethrough between the openings in said end walls; and control means providing for the passage of air through said heating conduit, said material, said cooling conduit and conditioned-air fan during dehumidification periods, and through said heating conduit, said material and said waste-air fan during reactivation periods and including means for operating said heating means only during reactivation periods.

WILLIAM R. ZUHLKE.
